(57) **CLAIM**

The ornamental design for a magnetized elastic bandage, as shown and described.

DESCRIPTION

FIG. 1 is a top plan view of a magnetized elastic bandage showing my new design, the opposite side being a mirror image of the shown;

FIG. 2 is a front elevation view thereof, the opposite end being a mirror image of the shown;

FIG. 3 is a right elevation view thereof, the opposite side being a mirror image of the shown;

FIG. 4 is an isometric view thereof; and,

FIG. 5 is a cross-sectional view taken along line 5-5 of FIG. 1. In FIGS. 1 and 3, the magnetized elastic bandage is shown in fragmentary form, portions thereof have been eliminated for ease of illustration. The broken lines in FIG. 4 depict environmental subject matter only and form no part of the claimed design.
